(57) **CLAIM**

The ornamental design for a powder duster, as shown and described.

DESCRIPTION

FIG. 1 is its combined state diagram of a powder duster, showing my new design;

FIG. 2 is a front perspective view thereof of its component 1;

FIG. 3 is a rear perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a front perspective view thereof of its component 2;

FIG. 11 is a rear perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof; and,

FIG. 17 is a bottom view thereof.

The broken lines in the drawings illustrate the portions of the powder duster, which form no part of the claimed design.

1 Claim, 17 Drawing Sheets
